US0D1050129S

(12) **United States Design Patent** (10) Patent No.: **US D1,050,129 S**
(45) Date of Patent: ** Nov. 5, 2024

(54) **HOUSING MODULE FOR AN ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **James A. Bertin**, San Jose, CA (US); **Daniele De Iuliis**, San Francisco, CA (US); **Markus Diebel**, San Francisco, CA (US); **David J. Dunsmoor**, San Jose, CA (US); **M. Evans Hankey**, San Francisco, CA (US); **Matthew David Hill**, Santa Clara, CA (US); **Julian Hoenig**, San Francisco, CA (US); **Richard P. Howarth**, San Francisco, CA (US); **Stoyan P. Hristov**, San Jose, CA (US); **Jonathan P. Ive**, San Francisco, CA (US); **Julian Jaede**, San Francisco, CA (US); **Duncan Robert Kerr**, San Francisco, CA (US); **David A. Pakula**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Ian Spraggs**, San Francisco, CA (US); **Christopher J. Stringer**, Woodside, CA (US); **Joe Sung Ho Tan**, Vienna (AT); **Tang Yew Tan**, San Francisco, CA (US); **Clement Tissandier**, San Francisco, CA (US); **Melissa A. Wah**, San Jose, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/898,011**

(22) Filed: **Jul. 21, 2023**

Related U.S. Application Data

(63) Continuation of application No. 29/850,631, filed on Aug. 22, 2022, now Pat. No. Des. 996,417, which is a continuation of application No. 29/648,095, filed on May 18, 2018, now Pat. No. Des. 961,594, which is a continuation of application No. 29/613,506, filed on Aug. 10, 2017, now Pat. No. Des. 831,025.
